JOHN GILBERT AND PETER M. SOFIELD, OF NEWARK, NEW JERSEY.

Letters Patent No. 75,896, dated March 24, 1868.

IMPROVEMENT IN THE MANUFACTURE OF WASH-BOWLS.

The Schedule referred to in these Letters Patent and making part of the same.

TO ALL WHOM IT MAY CONCERN:

Be it known that we, JOHN GILBERT and PETER M. SOFIELD, both of Newark, in the county of Essex, and State of New Jersey, have invented a new and useful Improvement in Sheet-Metal Wash-Bowls; and we do hereby declare that the following is a full, clear, and exact description of the same, reference being had to the accompanying drawings, making a portion of this specification, in which—

Figure 1 is a vertical transverse section of a wash-bowl constructed according to my invention.

Figure 2 is a detached side view of a portion of the same.

Similar letters of reference indicate corresponding parts in both figures.

In the ordinary method of constructing tin-ware, in which the supporting flange and bottom of the vessel are formed out of one piece of metal, the upper part is attached by soldering, as it were, edge to edge. This is found to be very weak, unless the solder is put on thick, in which case it has the appearance of work of an unskillful mechanic. The object of this invention is to form the connection both neater in appearance and stronger, and it consists in a supporting rim, formed in one piece, with a concave bottom, and constructed with a circumferential rebate, in which the lower edges of the flaring sides of the bowl are soldered, the desired objects being by this means effectually secured.

To enable others to understand the nature and construction of our invention, we will proceed to describe it with reference to the drawings.

The supporting rim of the bowl is marked *a*, and the sides thereof are in profile, curved or ogee-shaped, in order to give an ornamental appearance to the said rim. This rim *a* is formed of tin or other suitable sheet metal, and is made in one piece with the bottom, *b*, the latter being made concave, as shown more fully in fig. 1, and also represented in dotted outline in fig. 2. Formed at the periphery of this bottom, *b*, at the upper edge of the rim *a*, is an annular rebate, indicated at *a'*, which receives the lower edge of the flaring or sloping sides *c* of the bowl, the said edges being secured in the aforesaid rebate by soldering, as represented at *b'* in fig. 1.

By thus forming the rim and bottom in one, instead of two pieces; the labor of soldering the said parts to the sides of the bowl is materially reduced, and, inasmuch as the rim may be conveniently made of any suitable ornamental configuration during the operation of shaping the bottom formed therewith, the bowl is rendered much more ornamental in appearance, without in any way detracting from the economy resulting from the peculiarity of its construction.

What we claim as our invention, and desire to secure by Letters Patent, is—

The circumferential rebate *a'* around the base, *a*, substantially as shown and described, for forming the connection between the base and the upper part *c* of the vessel, as set forth.

JOHN GILBERT,
P. M. SOFIELD.
